UNITED STATES PATENT OFFICE.

JEROME B. SECOR, OF CHICAGO, ILLINOIS.

IMPROVEMENT IN SEWING-MACHINES.

Specification forming part of Letters Patent No. 121,965, dated December 19, 1871.

To all whom it may concern:

Be it known that I, JEROME B. SECOR, of Chicago, in the county of Cook and State of Illinois, have invented a new and useful Improvement in Sewing-Machines, of which the following is a specification, reference being had to the accompanying drawing.

The nature of my invention consists in the arrangement of the cam A that drives the needle-bar in a box, E, above the table of the sewing-machine, which enables me to drive the feed and shuttle from the same shaft that carries the cam, and arrange them all in a compact simple form above the table, and in the combination of the roller made with a raw-hide ring on a sleeve, with the cam-wheel A, and also in the combination and arrangement of the feeding device at the front of the machine, as hereinafter fully described.

Figure 1, Plate 1, represents a side elevation of my machine; Fig. 2, Plate 2, a front elevation. Fig. 3, Plate 3, represents a side elevation of the feed-bar and its attachments, enlarged; Fig. 4, a top or plan view of the same, with the crank and shuttle-carrier attached. Fig. 5 is a side elevation of the crank and shuttle-carrier detached. Fig. 6 is a detached view of the cam that drives the needle-bar.

A' is the frame or table of the machine. B is the treadle. C C¹ are the ordinary band-wheels for driving the machine. D is a shaft located above the table. E is a box or case inclosing the cam-wheel A. The cam-wheel is rigidly attached to the shaft D, and is revolved with it. F is a roller with a raw-hide shell, S, on a steel sleeve, S¹, which turns loosely on the end of the pin or stud S², Fig. 6. The stud S² is attached to the lower end of the needle-bar carrier S³ (shown on Fig. 1) by passing through it, and a nut, S⁴, being screwed on its other end. S⁵ is a slot in the box or case E for the rod S² to play back and forth in as the cam-wheel revolves, and gives the proper motion to the arm or needle-bar carrier S³, which is pivoted to the goose-neck at S⁶. There are two cams, e and e', on the front end of the shaft D for operating the feed-bars, as hereinafter described, and C is a crank rigidly attached to the shaft, and

revolved by it. C' is a pitman attached by ordinary wrist-pins to the crank C, and also to the bar C², which is attached to the shuttle-carrier C³. By the revolution of the shaft D the crank C is turned, and the shuttle operated so as to make the usual motions. l is a link or slotted bar pivoted to the machine at l¹. l² is the feed-bar, and is pivoted at one end to the pivoted link l at l¹, while the other end rests on the cam e, by which it secures a vertical motion as the cam revolves. l⁴ is a bar, one end of which is attached to the link l, as shown by the screw l⁵, while the other end passes around the cam e', which causes it to revolve the link l and give the lateral or horizontal motion to the feed-bar l². By moving l⁵ up or down in the link l the feed of the machine is varied and regulated. l⁶ is a thumb-piece by which the operator moves the connecting-rod l⁴ up or down in the link l to regulate the feed.

The operative parts of the machine are all placed together on the front of the machine, and are very simple and easily managed.

Having described the construction and operation of my invention, what I claim, and desire to secure by Letters Patent, is—

1. The cam-wheel A, shaft D, and inclosing-case E, arranged above the sole-plate of the machine, the shaft D carrying the cams e and e', and combined with and operating the feed-bar l² and connecting-rod l⁴, all substantially as and for the purposes set forth.

2. The needle-actuating arm S², its roller F, composed of the shell S and sleeve S¹, in combination with the cam-wheel A and slotted covering-case E, all constructed and arranged substantially as and for the purposes described.

3. The shaft D, the cams e and e', the feed-bar l², the slotted link l, and the connecting-rod l⁴ and screw l⁵, when all are constructed and arranged in a sewing-machine, as and for the purposes specified.

JEROME B. SECOR.
